ATTORNEY.

UNITED STATES PATENT OFFICE.

WALTER LEE CHURCH, OF HUMBLE, TEXAS.

WELL-DRILLING DEVICE.

1,330,736.

Specification of Letters Patent. Patented Feb. 10, 1920.

Application filed June 3, 1919. Serial No. 301,507.

To all whom it may concern:

Be it known that I, WALTER LEE CHURCH, a citizen of the United States, residing at Humble, in the county of Harris and State of Texas, have invented certain new and useful Improvements in Well-Drilling Devices, of which the following is a specification.

One object of the invention is to provide a device of the character described of the 10-percussion type, adapted to be attached to the lower end of a drill stem for drilling wells.

Another object of the invention is to provide a drilling tool, attached to the lower 15-end of the drill stem, and equipped with a bit and a reciprocating hammer, said hammer being actuated against the bit by hydraulic impulses, and withdrawn therefrom by mechanical means, said bit being thereby 20-actuated against the bottom of the bore to disintegrate the formation thereof.

With the above and other objects in view, the invention has particular relation to certain novel features of construction, operation 25-and arrangement of parts, an example of which is given in this specification and illustrated in the accompanying drawings, wherein:

Figure 1, is a vertical sectional view of 30-the lower part of the device.

Fig. 2, is a vertical sectional view of the upper part thereof.

Fig. 3, is a point view of the bit.

Fig. 4, is a transverse sectional view taken 35-on the line 4-4 of Fig. 1, and

Fig. 5, is a transverse sectional view taken on the line 5-5 of Fig. 1.

Referring now more particularly to the drawings wherein like numerals of reference 40-designate similar parts in each of the figures, the numeral 1, refers to a tubular barrel which is attached to the lower end of the drill stem 2, by means of the collar 3. Within the collar 3, there is a stuffing 45-box 4 through which the cylindrical hammer 5 reciprocates. The lower end of this hammer is formed with a detachable head 6, which plays through the spider 7, secured within the tubular coupling 8, which is 50-threaded onto the lower end of the barrel 1. The lower end of this coupling 8 has an inwardly extending annular shoulder 9, forming a bearing for the shank 10 of the bit 11. This shank is splined in the bearing 55-so that it will reciprocate therein, but be prevented from turning relative thereto.

The upper end of the shank is formed into an enlarged head 12, and threaded onto said shank below the coupling, there is a collar 13, said head and collar being spaced apart 60-a sufficient distance to permit a limited reciprocation of the shank and bit. The hammer 5 has an annular rib 14, spaced above the spider 7, and surrounding said hammer and interposed between said spider and rib 65-there is a strong coil spring 15.

In operation the device is let down into the bore until the bit rests on the bottom thereof and the stem is then filled with water, or other fluid. A force pump, (not 70-shown) is then connected to the upper end of the stem and with each forward stroke thereof, an impulse is transmitted through said fluid against the upper end of the hammer which is thereby actuated against the 75-head of the shank 10, and the bit is thereby driven against the formation at the bottom of the bore to disintegrate the same. Upon back stroke of the pump, the pressure is released, and the spring 15 will lift the bit out of contact with the formation preparatory to another stroke. The stem, during drilling operations, is slowly turned by any well known form of rotary and the bottom of the bore is thus gradually disintegrated and bore thus 85-deepened.

In order to wash away the cuttings from the bit, the entire device is elevated until the bit is lifted clear of the bottom of the bore, the head 12, then resting on the shoulder 9, and the bit being thereby suspended. The upper end of the hammer has a water 90-conduit 16, extending down and diverging out each way forming side ports 17, which are above the stuffing box 4, when the device 95-is in operation, but when the bit is suspended, as above explained, the fluid pressure from above will force the hammer downwardly until these ports are in position, to discharge water into the barrel 1, beneath the stuffing box 4, and the water then passes on down through the spider 7, and through the conduit 18, through the shank 10 and is discharged onto the blades of the bit and washes away the cuttings thereof and returns, laden with said cuttings, up through the bore on the outside of the stem. 100

What I claim is:

1. In a device of the character described, the combination with a drill stem, of a 110-drilling tool attached to the lower end thereof, and including a barrel, a bit formed

- with a shank which has a bearing in one end of the barrel, a hammer mounted for reciprocation in the barrel and adapted to be driven against the work by fluid impulses, 5 exerted through the stem in successive strokes against the shank of the bit, and a yieldable member connected to the hammer and normally operating in opposition to the fluid pressure exerted against said stem.
- 10 2. The combination with a drill stem, of a drilling tool, connected to the lower end thereof and including a barrel, a hammer therein, a yieldable seat whereon the hammer is mounted, a bit formed with a shank 15 which is movable lengthwise in a bearing carried by the lower end of the barrel, said hammer being adapted to be actuated with successive strokes against the bit, by fluid impulses exerted through the stem.

3. The combination with a drill stem, of 20 a drilling tool, connected to the lower end thereof, and including a barrel, a hammer therein, a yieldable seat whereon the hammer is mounted, a bit formed with a shank which is movable lengthwise in a bearing 25 carried by the lower end of the barrel, but which is keyed against rotation relative thereto, said hammer being adapted to be actuated with successive strokes against the bit, by fluid impulses exerted through the 30 stem.

In testimony whereof I have signed my name to this specification in the presence of two subscribing witnesses.

WALTER LEE CHURCH.
